(57) **CLAIM**

The ornamental design for a wireless touchscreen hand controller with charger set, as shown and described.

DESCRIPTION

FIG. 1 is a perspective view of a wireless touchscreen hand controller with charger set showing my new design wherein the wireless touchscreen hand controller is not inside the charger;

FIG. 2 is a second perspective view thereof;

FIG. 3 is a third perspective view thereof;

FIG. 4 is a fourth perspective view thereof;

FIG. 5 is a front elevational view of the wireless touchscreen hand controller with charger set wherein the wireless touchscreen hand controller is inside the charger;

FIG. 6 is a rear elevational view of FIG. 5;

FIG. 7 is a left side view of FIG. 5;

FIG. 8 is a right side view of FIG. 5;

FIG. 9 is a top plan view of FIG. 5;

FIG. 10 is a bottom plan view of FIG. 5;

FIG. 11 is a first perspective view of FIG. 5;

FIG. 12 is a second perspective view of FIG. 5;

FIG. 13 is a third perspective view of FIG. 5; and,

FIG. 14 is a fourth perspective view of FIG. 5.
